UNITED STATES PATENT OFFICE.

JOHN P. EISENHAUER, OF PORT HURON, MICHIGAN.

FILING-ENVELOP FOR PHONOGRAPH DISK RECORDS AND OTHER FILING PURPOSES.

1,154,297.

Specification of Letters Patent. Patented Sept. 21, 1915.

Application filed May 7, 1913. Serial No. 766,228.

To all whom it may concern:

Be it known that I, JOHN P. EISENHAUER, a citizen of the United States, residing at Port Huron, county of St. Clair, and State 5 of Michigan, have invented a new and useful Improvement in Filing-Envelops for Phonograph Disk Records and other Filing Purposes, of which the following is a full, clear, and exact description.

10 The invention relates to improvements in filing envelops for disk records and documents and papers of every description.

15 The object of the present invention is to improve the construction of filing envelops, more especially the containers for disk records and to provide a simple, practical and efficient envelop adapted to hold disk records and papers of every description in an orderly manner and at the same time allow 20 ready and convenient access to any desired record or paper without unnecessary handling of disks of records not desired.

With these and other objects in view the invention consists in the construction and 25 novel combination and arrangement of parts hereinafter fully described, illustrated in the accompanying drawings and pointed out in the claims hereto appended, it being understood that various changes in the form, 30 proportion and minor details of construction may be resorted to without departing from the spirit or sacrificing any of the advantages of the invention.

In the drawing Figure 1 is a face view 35 of a filing envelop embodying my invention, Fig. 2 is an elevation of the open end of the envelop.

Like numerals of reference designate corresponding parts in all the figures of the 40 drawing.

In the accompanying drawing in which is illustrated the preferred embodiment of the invention, 1 designates a filing envelop constructed of a single piece of flexible material such as paper and folded centrally at 2 to form two side walls 3 and 4 and to provide a closed rear end. The outer end 3 of the filing envelop is open to provide an open front 3^a for the introduction of a disk or 45 other record and the said side walls are designed to be provided with recesses 5, to facilitate the ready removal of the contents of the filing envelop. The side wall 3 is provided at its side edges with inturned flaps 6 and 7 which are secured by adhesive ma-

terial to the inner face of the side wall 4 to close the filing envelop at the side edges throughout the entire length thereof. The other side wall 4 is provided at one of the side edges of the envelop with a flexible flap 60 8 extending exteriorly of the envelop and adapted to bear identification matter.

The flexible flap 8 which may extend outwardly as illustrated in dotted lines in Fig. 2 of the drawing is also capable of being 65 folded inwardly against the exterior of the side wall 3 when desired. The projecting or exteriorly arranged flap 8 enables the contents of the filing envelop to be readily ascertained at a glance and when a large number of filing envelops are placed within a casing or container, the contents thereof may be easily and quickly examined and the desired record or records may be removed 70 without unnecessary handling of records not 75 desired.

The extension identification flap may be located at any one of the closed edges of the envelop and the latter may be made of any desired dimensions and in various forms. 80 The identification flap by being flexible forms a hinged connection with the envelop and the flaps of a number of filing envelops may be easily depressed by the fingers of either hand so that the titles may instantly 85 be brought to view with almost the same motion as running through the leaves of a book.

The filing envelop is also useful for many 90 purposes where more extensive filing systems would be inapplicable, such as filing photographic negatives, sheet music and the like, the plan of handling such articles being precisely the same as with disk records.

The method of individual filing by title 95 or subject matter will be found superior to collective or alphabetical filing where but a limited number of articles are to be filed, as no systematic replacement of articles removed for use from a cabinet or other filing 100 receptacle need be observed.

This invention enables identifying tabs to be applied to various articles without injury or defacement of such articles. It affords a protection to such articles and it provides 105 an easy method for pamphlets and articles not thick enough to have the necessary identification data stamped upon the edge or back which is usually exposed to view in a filing receptacle for such articles.

What is claimed is:—

1. A filing envelop of the class described consisting of a single sheet of paper folded centrally to form two side walls and a connecting bend which closes the rear end of the envelop, the front end of the envelop being open for the insertion and removal of a disk or other record, said side walls being united at their side edges to close the envelop at said points, said envelop being provided at one of its closed side edges with a narrow longitudinal exteriorly arranged identification flap adapted to be either folded against the envelop or arranged in a projecting position.
2. A filing envelop of the class described consisting of a single sheet of paper folded centrally to form two side walls and a connecting bend which closes the rear end of the envelop, the front end of the envelop being open for the insertion and removal of a disk or other record, said side walls being united at their side edges to close the envelop at said points, said envelop being provided at one of its closed side edges with a narrow longitudinal flap formed integral with one of the side walls of the envelop
3. A filing envelop consisting of a single piece of flexible material folded to form two side walls and a connecting bend which closes the rear end of the envelop, the front end of the envelop being open, one of the side walls being provided at its side edges with narrow longitudinal flaps secured to the other side wall, the latter side wall being provided at one of its side edges with an outturned exteriorly arranged narrow longitudinal flap extending along one of the closed side edges of the envelop and adapted to bear identification matter.
4. A filing envelop open at one edge and closed at the other edges and provided at one of its closed edges with an integral extension identification flap extending along such closed edge and located beyond the side walls of the envelop without cutting the said side walls.

JOHN P. EISENHAUER.
